FISHING LINE RECEIVING ADAPTOR SPOOL

Larry L. Lilland and James T. Rumbaugh, Spirit Lake, Iowa, assignors to Berkley & Company, Inc., Spirit Lake, Iowa

Division of design application Ser. No. 16,979, May 1, 1969, which is a continuation-in-part of design application Ser. No. 11,853, May 9, 1968, and a division of design application Ser. No. 16,982, May 1, 1969, all now abandoned. Divided and this application Feb. 5, 1971, Ser. No. 113,111

Term of patent 14 years

U.S. Cl. D8—220   Int. Cl. D8—99

FIG. 1

FIG. 2

FIG. 3

FIG. 4

FIG. 5

FIG. 1 is a perspective view taken along the top edge surface of the fishing line receiving adaptor spool design of the present invention and showing one of the flanges provided with slots partially through the surface of the flange;

FIG. 2 is a rear elevational view showing the adaptor spool of FIG. 1;

FIG. 3 is a vertical sectional view taken along the line and in the direction of the arrows 3—3 of FIG. 2;

FIG. 4 is a view similar to FIG. 1 illustrating a modified form of slot formed in one of the flanges; and

FIG. 5 is a view similar to FIG. 1 and showing a modified form of slot formed in one of the flanges.

The present application being a divisional application of our co-pending application Ser. No. D. 16,979, filed May 1, 1969, now abandoned, which application was a continuation-in-part of application Ser. No. D. 11,853,

filed May 9, 1968, now abandoned. The present application is further a divisional application of co-pending application Ser. No. D. 16,982, filed May 1, 1969 now abandoned.

We claim:

The ornamental design for a fishing line receiving adaptor spool, as shown and described.
